US0D1059693S

(12) **United States Design Patent** (10) **Patent No.:** **US D1,059,693 S**
(45) **Date of Patent:** **** Jan. 28, 2025**

(54) **BIRD FEEDER**

(71) Applicant: **Pengchuangda (Shenzhen) Industrial Co., Ltd.**, Shenzhen (CN)

(72) Inventor: **Zechuang Zheng**, Shenzhen (CN)

(73) Assignee: **Pengchuangda (Shenzhen) Industrial Co., Ltd.**, Shenzhen (CN)

(**) Term: **15 Years**

(21) Appl. No.: **29/883,011**

(22) Filed: **Jan. 23, 2023**

(51) LOC (15) Cl. **30-03**

(52) U.S. Cl.

USPC **D30/124; D30/126**

(57) **CLAIM**

The ornamental design for a bird feeder, as shown and described.

DESCRIPTION

FIG. 1 is a first perspective view of a bird feeder showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the bird feeder thereof.

The broken lines shown in the drawings depict portions of the bird feeder that form no part of the claimed design.

1 Claim, 9 Drawing Sheets
